The ornamental design for a combined telephone handset with charging unit, as shown and described.

DESCRIPTION

FIG. 1 is a front, right side, perspective view showing our new design in which the telephone handset is separated from the charging unit;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a front, right side, perspective view showing our new design in which the telephone handset is integrated with the charging unit.

FIG. 7
